CLAIM

(51) LOC (7) Cl. **14-02**

The ornamental design for an electronic computer, as shown and described.

(52) U.S. Cl. **D14/318**

DESCRIPTION

(58) Field of Search D14/315-327;

FIG. 1 is a top, front and right side perspective view of an electronic computer showing my new design,

D18/1, 2, 7; 235/145 A, 145 R; 341/22,
23; 345/104, 156, 168, 169, 173; 361/380-686;
400/486, 489

FIG. 2 is a front elevational view thereof,

(56) References Cited

FIG. 3 is a rear elevational view thereof,

U.S. PATENT DOCUMENTS

FIG. 4 is a left side elevational view thereof,

D338,879 S * 8/1993 Iino D14/316

FIG. 5 is a right side elevational view thereof,

D415,474 S * 10/1999 Goto D14/318

FIG. 6 is a top plan view thereof,

D435,549 S * 12/2000 Amano et al. D14/318

FIG. 7 is a bottom plan view thereof,

6,205,021 B1 * 3/2001 Klein et al. 361/683

FIG. 8 is a front elevational view showing the article in a

D453,756 S 2/2002 Kamegi

closed position thereof,

D479,841 S 9/2003 Tago et al.

FIG. 9 is a right side elevational view showing the article in the

D481,386 S 10/2003 Kondo

closed position thereof; and,

FOREIGN PATENT DOCUMENTS

FIG. 10 is a top plan view showing the article in the closed
